UNITED STATES PATENT OFFICE.

HARRY G. LEE, OF TACOMA, WASHINGTON.

REVOLVING GRATE.

1,320,481.

Specification of Letters Patent. Patented Nov. 4, 1919.

Application filed December 4, 1917, Serial No. 205,342. Renewed September 24, 1919. Serial No. 325,964.

To all whom it may concern:

Be it known that I, HARRY G. LEE, a citizen of the United States, residing at Tacoma, in the county of Pierce and State of Washington, have invented certain new and useful Improvements in Revolving Grates, of which the following is a specification.

The invention relates to grates particularly adapted for furnaces, and aims to secure a positive draft, to prevent the burning and warping of the grate bars, to free the fuel bed from ashes and clinkers, and to prevent obstructing of the grate bars.

The invention consists of hollow grate bars mounted to receive a rotary movement and strengthened and reinforced by longitudinal ribs which also serve to maintain air spaces between the fuel and the bars, as also to engage and crush clinkers and insure their discharge into the ash pit.

The invention also consists of a self-closing clean-out at the rear of each grate bar which may be pressed open to admit of accumulations escaping, the grate bars being mounted in a manner to positively direct the accumulations into the ash pit.

The invention furthermore consists of novel means for supplying air, steam or like medium to the grate bars from a header or conduit common to all the grate bars, said header or conduit having clean-out openings opposite the several grate bars which are covered by suitable closing means.

For a full understanding of the invention and the merits thereof, reference is to be had to the following description and the drawings hereto attached, in which—

Figure 1 is an elevation of a furnace grate embodying the invention, parts being broken away, and partly in section.

Fig. 2 is a front view, parts being broken away.

Fig. 3 is a sectional detail showing the parts on a larger scale.

Fig. 4 is a sectional detail of the rear portion of a grate bar showing the parts on a larger scale, and

Fig. 5 is a transverse section of a grate bar.

Corresponding and like parts are referred to in the following description and indicated in the several views of the drawings by like reference characters. The furnace illustrated is of ordinary construction, and is shown to depict the application of the invention, and comprises a front wall 1, a bridge wall

2, fire chamber 3 and an ash pit 4. The bridge wall 2 is formed in its forward side with a recess, the bottom wall 5 of which inclines forwardly and downwardly so as to 60 direct ashes and other accumulations discharged from the rear of the grate bars into the ash pit 4.

The grate may comprise any number of bars 6 which may be of any length or diameter, and which are hollow and mounted in a manner to receive a rotary movement. As indicated in Fig. 1, the grate bars 6 are mounted at their ends and intermediate their ends.

To reduce the friction to the 70 smallest amount possible, the bearings are preferably of the anti-friction type, and are shown as comprising rollers. Each of the grate bars is formed upon its outer surface with a plurality of longitudinally disposed ribs 7, which serve to reinforce and strengthen the grate bar, as also to preserve air spaces, and to engage and positively crush clinkers and insure a discharge of ashes and other matter, so as to maintain 80 a fuel bed containing a minimum amount of ashes, clinkers and the like. The ribs 7 are formed at intervals in their length with openings 8 for the escape of air, steam or other medium supplied to the grate bars for 85 promoting combustion of the fuel. The grate bars are open throughout their length and the rear of each grate bar has an outstanding flange 9 against which the plate 10 closes,

being yieldably pressed forward by means 90 of expandible yieldable springs 11, which are mounted on guide rods 12 projecting rearwardly from the grate bar. A yoke 13 receives the rear ends of the guide rods 12 and holds them in given position. The 95 springs 11 are supported on the guide rods 12 and the latter likewise support the plate or closure 10.

A header or conduit 14 is disposed in front of the furnace and extends transversely thereof, and is provided in its front side with a plurality of openings 15 in line with the respective grate bars 6. The openings 15 are closed by suitable covers 16. Each of the grate bars is provided at its 105 outer or forward end with a hollow journal 17 which is mounted in the rear side of the header or conduit 14. The hollow journal 17 may be provided in any manner, either as a part of the grate bar or as a tube 110 secured thereto. A stuffing box 18 of approved construction co-operates with each of

the hollow journals 17 to maintain a close joint between the journal and header. A gear wheel 19 is secured to the projecting end of each grate bar, and the gear wheels 19 are of a diameter so as to intermesh, whereby rotary movement imparted to one of the grate bars is transmitted to each of the grate bars. A ratchet wheel 20 is secured to the projecting end of one of the 10 grate bars and coöperates with a pawl 21 mounted upon a lever 22, which is supported upon the journal of the grate bar provided with the ratchet wheel 20. The lever 22 may be operated in any manner and may be connected with a moving part by means of a rod or like connection 23.

The header or conduit 14 is adapted to be connected with a blower or other source of fluid supply, such as steam or compressed 20 air. The compressed air or other fluid medium passes through the header or conduit 14 through the hollow journals 17 into the respective grate bars, and escapes through the openings 8 thereof into the fuel bed 25 and promotes combustion as will be readily understood. In the event of ashes or other material accumulating in the grate bars, the latter may be cleaned by introducing a brush or other device through the openings 30 15 of the header and passing such brush or cleaner through the grate bars, the closure 10 yielding to admit of the ashes or other material escaping and passing into the ash pit in the manner herein stated. The grate 35 bars may be rotated by hand or by suitable mechanism, and in the event of the furnace being fed by means of a mechanical stoker, the rod or part 23 may be connected to a moving part of the mechanism so as to impart a regular oscillatory movement to the 40 45 lever 22, whereby the grate bars are slowly rotated so as to keep the fuel bed clear of ashes and clinkers.

It is observed that practically as much air 45 will enter the ash pit as is directed through the fuel bed. By closing the ash pit, the air is caused to pass therefrom through the fire and the draft may be regulated by causing the fan blower to rotate at a greater or 50 less speed. By this means the fire may be forced, if necessary, by speeding the fan blower.

I claim:—

1. A hollow grate bar provided in its 55 length with a plurality of outlets and opened throughout its length, a closure for covering the rear end of the grate bar, a guide for supporting the closure and a spring mounted on said guide and yieldably holding the closure seated.

2. A hollow grate bar open throughout its length and provided with a plurality of lateral outlets, guide rods projecting from the rear of the grate bar, the closure mounted upon the guide rods and normally covering the rear end of the grate and springs mounted upon the guide rods and normally exerting a pressure to hold the closure seated against the rear end of the grate bar. 65

3. A furnace embodying a wall at the rear 70 of the fire chamber, said wall having a recess in its forward side with its bottom forwardly and downwardly inclined, a hollow grate bar open throughout its length and having its rear end mounted in the recess of 75 the inner wall, and a closure yieldably held against the rear end of the grate bar to normally cover the same.

4. A furnace grate comprising a plurality of hollow grate bars having discharge openings at their rear ends and provided in their 80 length with a plurality of lateral outlets, closures normally covering the rear ends of the grate bars, a header connecting the front ends of the grate bars and in communication therewith and provided in its front side with a plurality of openings in line with the openings of the respective grate bars, and closures for the openings of the 85 header.

5. A furnace embodying a wall at the rear 90 of the fire chamber, said wall having a recess in its forward side with its bottom forwardly and downwardly declined, a hollow grate bar open throughout its length and 95 provided with a lateral outlet intermediate its ends and having its rear end mounted in the recess of the inner wall, and a closure to normally cover the rear end of the 100 grate bar.

6. A furnace embodying a bridge wall formed in its forward side with a recess having a forwardly and downwardly inclined bottom discharging into the ash pit, a plurality of hollow grate bars rotatably 105 mounted in the front and bridge walls of the furnace and having openings in their length and a discharge opening at the rear, a closure yieldably held against the rear end of each grate bar and disposed within the 110 recess of the bridge wall, means connecting the grate bars to cause them to rotate in unison, a header provided in its front side with openings opposite the respective grate bars, closures for such openings, and hollow journals forming connecting means between the respective grate bars and the header. 115

In testimony whereof I affix my signature.
HARRY G. LEE.
